UNITED STATES PATENT OFFICE

1,934,522

BURIAL VAULT

Walter C. Broughton, Kansas City, Mo.

Application February 5, 1932. Serial No. 591,111

2 Claims. (Cl. 72—7)

My invention relates to certain new and useful improvements in burial vaults of that type which are placed in the grave for the reception and protection of the coffin or casket, and one object 5 is the provision of a vault of this character which will effectively exclude water or moisture from the casket placed therein for protection.

A further object is to provide a vault composed preferably of parts which can be readily lowered 10 piece by piece and assembled in the grave, thereby avoiding the expense of transporting a heavy object of this character made in one unit at a factory and lowering it into the grave, operations requiring special apparatus and a large 15 amount of labor.

Another object is to provide a substantial burial vault which can be constructed at minimum expense, and in order that the invention may be readily understood reference will now be had to 20 the accompanying drawing, in which:

Fig. 1 is a longitudinal horizontal section on line 1—1 of Fig. 2, showing the vault in position in a grave.

Fig. 2 is a vertical longitudinal section on line 25 2—2 of Fig. 1.

Fig. 3 is a cross section on line 3—3 of Fig. 2.

Fig. 4 is a detail perspective view of one of a pair of sills employed in carrying out the invention.

30 Referring in detail to the different parts, 2, 2, designate a pair of sills having longitudinal offsets 4 in which the walls of an outer case 6 are adapted to be seated. The outer case 6 is open at its top and bottom and comprises end walls 8 and side walls 10. Preferably, the end and side walls 8 and 10, respectively, are separate 35 from each other so that they can be lowered into the grave A one by one and seated in the offsets 4 of the sills 2. Any suitable means may be employed for connecting the end walls 8 to the side walls 10. In the present instance I have shown such means in the form of wires 12 secured to the respective walls 8 and 10 and their other ends free to be twisted together. As a 40 further means of holding the walls 8 and 10 together certain of said walls, in the present instance the side walls 10, are notched at their ends as indicated at 14 for the reception of the ends of the walls 8 as shown by Fig. 1.

50 16 designates an inner case which, like the outer case, may be left open at the top and bottom to reduce the cost of construction to a minimum. In the present instance, however, I have shown said inner case comprising a bottom wall 17, end walls 18 and side walls 20, which latter

are preferably notched at their ends as indicated at 22 for the reception of the ends of the walls 18. The end and side walls 18 and 20, respectively, are secured together by suitable means such as wires 21 arranged similar to the wires 12. 60 The bottom wall 17 has a marginal offset 23 for the reception of the lower edges of walls 18 and 20 and to cooperate with the wires 21 in holding said walls 18 and 20 in place.

The outer case 6 is enough larger than the 65 inner case 16 to leave an intervening space which surrounds the latter for the reception of a waterproof material 30. The walls of the inner case 16 are of less height than those of the outer case as shown by Figs. 2 and 3, so that when 70 a lid 26 is placed upon the inner case and slabs 28 are placed upon the outer case space will be left for material 30 which is also employed to fill in the space between the end and side walls 75 of the outer and inner cases.

In practice the vault may be readily installed in the grave as follows: The sills 2 are placed at the ends of the bottom of the grave, after which said bottom is covered with a layer of asphalt, liquid pitch, or other suitable cementitious waterproof 80 material 30. The walls of the outer case 6, if made separate as preferred, are then lowered one by one into the grave and assembled with the end walls 8 resting in the offsets 4 of the sills 2 and the ends of the side walls 10 also resting in said 85 offsets, the flanges 32 extending around the offsets forming a gage for proper placement of the end and side walls 8 and 10, respectively. The bottom wall 17 is then placed upon the waterproof bottom 30 after which drain tubes 36 are 90 installed in openings in said bottom wall 17 and forced through the cementitious bottom layer 30 and into the ground for the purpose of carrying off any moisture from the body within the casket. The end and side walls 18 and 20, respectively, of 95 the inner case are then lowered upon the bottom wall 17 and connected together in the same manner as the walls of the outer case 6. The space surrounding the inner case 16 is then filled with additional material 30 after which the casket, 100 not shown, is placed within the inner case 16. The lid 26 is then placed upon the upper edge of the walls 18 and 20 and covered with additional material 30, which together with the other material 30 already placed in position, forms a continuous waterproof closure completely surrounding the inner case 16 and its lid 26. If the material 30 is of a kind that quickly sets it may not be necessary to utilize the planks or slabs 28, but if 105 a kind that sets slowly the planks or slabs are 110

placed upon the outer case 6 to protect the top layer 30 from becoming damaged when the grave is refilled with the earth removed during the excavating operation.

5 The walls of the outer and inner cases 6 and 16, respectively, may be made of wood or metal as the material 30 when set forms a substantial protection for the casket, but preferably said walls, the lid 26 and the members 28 are constructed 10 of concrete or like cementitious material which will last indefinitely and provide additional strength for the vault.

From the foregoing description it is apparent that I have provided a burial vault possessing the 15 advantages above pointed out, and while I have shown one form of said vault, I reserve all rights to such other forms and modifications thereof as properly fall within the spirit and scope of the invention as claimed.

20 Having thus described my invention, what I claim and desire to secure by Letters Patent, is:

1. A vault of the character described comprising inner and outer cases open at their bottoms

and spaced apart to leave an intervening space, a lid to said inner case, a pair of sills upon which the ends of the outer case rest, a layer of waterproof material covering the space between the sills and upon which said cases rest, waterproof material filling the space between the cases, and waterproof material covering the lid of the inner case and cooperating with the other waterproof material in forming a continuous wall entirely enclosing said inner case.

2. A vault of the character described comprising a pair of sills each having a longitudinal and end flanges which cooperate in forming an offset in the respective sills, an outer case including end walls resting in said offset and against the respective longitudinal flanges, and side walls having their ends resting in the offsets and against the respective end flanges; an inner case spaced from and arranged within said outer case, and waterproofing material filling the space between the inner and outer cases.
